CLAIM

The ornamental design for a miniature two-sided picture frame, substantially as shown and described.

DESCRIPTION

FIG. 1 is a front elevational view of a miniature two-sided picture frame showing my new design, the opposite side being a mirror image thereof.

FIG. 2 is a top plan view thereof.

FIG. 3 is a left end elevational view thereof.

FIG. 4 is a right end elevational view thereof.

FIG. 5 is a cross-sectional view taken along line 5—5 of FIG. 1.
